UNITED STATES PATENT OFFICE.

GEORGE W. MERROW AND JOHN T. COLLINS, OF HARTFORD, CONNECTICUT,
ASSIGNORS TO THE MERROW MACHINE COMPANY, OF HARTFORD, CONNECTICUT, A CORPORATION OF CONNECTICUT.

EDGING FOR LACE.

SPECIFICATION forming part of Letters Patent No. 718,139, dated January 13, 1903.

Application filed September 15, 1897. Serial No. 651,772. (No specimens.)

To all whom it may concern:

Be it known that we, GEORGE W. MERROW and JOHN T. COLLINS, citizens of the United States, residing at Hartford, in the county of 5 Hartford and State of Connecticut, have invented certain new and useful Improvements in Edging for Lace; and we do hereby declare the following to be a full, clear, and exact 10 description of the same, reference being had to the accompanying drawing, forming a part of this specification, and to the letters of reference marked thereon.

The object of our present invention is to produce economically and rapidly a superior 15 edge finish for lace or similar open-work fabrics, one closely simulating a selvage finish, harmonizing with the general texture of the goods, and constituting a durable and inexpensive protective and ornamental border for the cut edges of open-work fabrics.

Heretofore in the manufacture of lace curtains and similar articles constructed from open-work fabric it has been the custom to cut or trim the edges of the fabric on the desired lines—such as scallops, points, &c.—and then apply a binding-tape to the cut edges, or, as a substitute therefor, to lay one or more cords along the cut edge and apply overseam stitches thereto, the overseaming engaging 30 the edge of the fabric and embracing the cord or cords, so as to confine the latter in place. The products of both of said methods are defective, the first being clumsy and unattractive, besides being expensive, while the second is deficient in strength and enduring qualities, there being no sufficient support for the overedge-stitches, especially at the more open portions of the work, while the thread or threads laid along the cut edges being 35 loosely embraced by the overedge-stitches draws out easily, thereby greatly impairing the appearance and stability of the edge. To overcome these and other defects incident to the finishes referred to, we apply a line of 40 straight-ahead stitches, either single or double thread, near the edge of the lace, following the outline of the edge desired, and then apply overedge-stitches, so as to cover the edge and engage the line of straight-ahead 45 stitching. The effect of this is to reinforce

the edge of the fabric, by means of the line of straight-ahead stitches, by connecting and binding together the threads and bridging the intervals where the work is more open by a connected chain of stitches, so that when 55 the overedge-stitching is applied it will embrace and be supported by the line of straight-ahead stitches and form a secure and ornamental finish, possessing the requisite body, completely covering and protecting the cut 60 edges. The trimming of the fabric may be performed either before, after, or during the application of the line of straight-ahead stitches, a sufficient margin being left beyond said line of foundation-stitches to insure 65 their firm attachment to the fabric, thus not only reinforcing the cut edge, but forming a secure bridge across the larger intervals or meshes.

Any of the well-known overseaming or over-edge stitching-machines or methods may be employed to form the final finishing edge, either single or double thread stitches being used for the purpose, although we prefer to make use of a double-thread overseam-stitch 75 such as that formed by the machine of the Merrow patent, No. 591,049, dated October 5, 1897, as it has been found to produce a very neat, ornamental, and durable edging when applied in connection with the foundation-line 80 of straight-ahead stitches, as hereinbefore explained.

The accompanying drawing serves to illustrate our invention.

The open-work lace fabric A is cut or 85 trimmed in the form of points and scallops, resulting in the production of what is known as a "raw" edge B, composed of the loose ends of the severed threads of the fabric situated at different distances apart and projecting at 90 different angles, with comparatively wider intervals of irregular extent. Within the body of the fabric, near the cut edge, is formed a line of straight-ahead stitches C, which latter serve not only to reinforce the weakened edge, 95 but also add to the body thereof and form a connection or bridge, as at a, spanning the larger gaps in the edge of the fabric, so that when the overedge stitching or finish D is applied it will be supported and held secure, 100

not by the weakened and mutilated edge of the fabric alone, but by the fabric reinforced by the line of stitches C. In passing across the larger intervals the overedge-stitches D 5 embrace the line of stitches C, which latter being formed in and secured to the body of the fabric becomes in effect a part thereof, affording a secure basis upon which to form a continuation of the overedge finish, which 10 elsewhere embraces and hides the projecting ends of the threads.

As before mentioned, any suitable means may be employed for forming the line of stitches C near the cut edge of the fabric; but 15 we prefer to use a sewing-machine provided with an automatic trimming attachment, as by so doing we are enabled to perform the two operations at once, at the same time properly locating the line of foundation or marginal stitches C at the proper distance from 20 the cut edge. It is obvious, however, that the formation of the line of stitching C may either precede or follow the trimming or both take place at the same time, the only required 25 site being the application of the foundation

chain of stitches in the fabric at a short distance from the raw edge and running lengthwise thereof to serve as a foundation to receive the finishing overedge-stitches.

Having thus fully described our invention, 30 what we claim as new, and desire to secure by Letters Patent, is—

As a new article of manufacture a fabric having spaces therein forming open-work designs extending out at the edge of the fabric, 35 with a line of straight-ahead stitching connecting the threads of the fabric and bridging the spaces such stitching being in proximity to but at a uniform distance from the edge of the fabric to form a foundation for overedge 40 stitching and overedge stitching embracing said line of straight-ahead stitching and the edge of the fabric to form a finished edge; substantially as described.

GEORGE W. MERROW.
JOHN T. COLLINS.
